PERCUSSION DEVICE

William M. Drennon, Anaheim, Calif., assignor of
one-third to Collins Mason, Beverly Hills,
Calif.

Application September 11, 1939, Serial No. 294,239

6 Claims. (Cl. 255—42)

My invention has to do with percussion devices and, in its more particular aspects, relates to pneumatic hammers of the class wherein a reciprocating plunger element is brought into forceable impact against a drill or the like.

An object of the invention resides in the provision of a device of this class in which the hammer plunger is raised by mechanical means and the impacting blow is caused by fluid under pressure.

Another object is the elimination of all possible springs inasmuch as springs in a tool of this type rapidly deteriorate and crystallize and require frequent renewal.

Another object is the provision in such a device of means for rotating the percussion tool during operation.

Another object is to provide in such a device means connected with the mechanical element employed to raise the hammer plunger, for delivering fluid under pressure to a pressure chamber.

Another object is to provide a pneumatic percussion device which requires a minimum of fluid for its operation.

Another object is to provide a durable, simple and efficient percussion device which may be portable, compact and economical of manufacture.

Other objects and corresponding attainments of my invention will become obvious to those skilled in the art from the particular adaptation thereof which I illustrate in the accompanying drawings and describe hereinafter.

In the drawings:

Fig. 1 is a vertical section of my device, with some parts being shown in elevation;

Fig. 2 is a section on line 2—2 of Fig. 1;

Fig. 3 is a section on line 3—3 of Fig. 1;

Fig. 4 is a section on line 4—4 of Fig. 1; and

Fig. 5 is a sectional view similar to Fig. 2 but showing the hammer plunger in its lower extreme position.

In general, I carry my invention into practice by providing a hammer which is in the form of a plunger having its upper end in communication with a fluid pressure chamber, which chamber is kept charged with fluid under suitable compression by a pump, which pressure imparts the striking force to the plunger. The hammer is raised after each stroke by means of a cam rotated by a drive shaft connected to a suitable power means, said drive shaft also operating the pump. A train of gears operatively connected to the drive shaft continually rotate the

percussion tool being impacted by the hammer, such tool being slidably mounted in an axial opening in one of the gears of said train.

Referring now to the drawings, I show a body 5 having bottom end plate 6 secured to it by screws 7, a side plate 8 secured by screws 9, an opposite side plate 10 secured by screws 11 and a top cover plate 12 secured by screws 13, said top plate covering a recess formed in the top 10 of the body to provide a fluid pressure chamber 15. A top handle 16 is preferably formed integral with plate 12 and a side handle 17 is secured to the body by screws 18.

The body is provided with a longitudinal bore 20 in which is slidably mounted a hammer plunger 21, the top of which communicates with chamber 15 and is provided with a cup washer 24 secured to its end by screw 25, and which plunger is slidably carried at its end in bushing 26, which bushing is threaded mounted in the enlarged top end of bore 20 and has tool receiving slots 26a to facilitate its removal. Plunger 21 is round in cross section except for that portion 30 intermediate its end, which is flattened 25 to provide opposite shoulders 31, 32. The lower end of hammer 21 is provided with a longitudinal bore 35 within which is slidably mounted the anvil member 36, which anvil is provided with a head 37. The lower end of the hammer is slidably mounted in bushings 40, 41 and packing gland 42.

The bottom end of the body is provided with a recess 45 within which the tool holding end rotating assembly to be later described is housed, 35 said recess being covered by end plate 6.

Extending transversely of the body and journaled in ball bearings 50, 51 and 52 is a drive shaft 55. Secured to the drive shaft within body recess 60, which recess is closed by screwthreaded 40 plug 61, there is a bevel gear 62. Secured to one end of shaft 55, I provide cams 64, 65, which rotate on opposite sides of the flattened portion 30 of the hammer plunger and are adapted to engage the cam surfaces provided by key member 67, which key is force-fitted into a transverse hole 67a in the plunger, the upper curved portion of the key fitting into socket portions 68 provided in the shoulder 31 of the plunger, and the key being secured in position by a pin 69. 45 A power transmitting shaft 70 is journaled in bearings 71, 72 and 73 and carries pinion gear 74 which meshes with larger gear 75 secured to drive shaft 55, the outer end of shaft 70 having annular flange 77 and being socketed at 78 to receive the end of a flexible shaft 80 which leads

to a suitable power means, not shown, such as an electric motor. Shaft 10 is held against longitudinal movement in its bearings by flanged sleeve 82 which is threadedly mounted on the threaded portion 83 of end plate 10.

Operatively connected to the inner end of drive shaft 55, by crank 91 and connecting rod 90, there is a pump plunger 92 which is slidably mounted in a cylinder bore 95 provided in the body. At the top end of the bore 95 there is a plug 100 which has a central bore 101 in which is mounted a spring pressed ball valve 102, whose spring 103 seats at its lower end against ball 102 and at its top end against screwthreaded plug 104. Mounted in the bore of a plug 110, which forms a closure for opening 109 extending from chamber 15 to atmosphere, there is a spring pressed ball safety valve 111 whose spring is held against the valve by plug 112 which has an outlet port 115 communicating to atmosphere.

Journalled in ball bearing 120, in end plate 6, there is a percussion tool holding sleeve 121 which carries an integral gear 122 and which has a bore of square cross-section to receive the similarly shaped end of a tool T, such as a drill or the like. A packing washer 125 surrounds the lower end of sleeve 121 and is held against longitudinal escape by the flanged sleeve 126 threadedly mounted on end plate 6 and by sleeve 126a. Mounted over gear 122 within body recess 45, by force fit, are parallel plates 131, 132, there being confined between said plates a rubber cushioning washer 133, each of said plates and said washer having a central opening 134 through which the upper end of tool T projects.

Gear 122 is operatively connected to drive shaft 55 by means of pinions 140, 141, vertical shaft 142 and bevel gear 143. Shaft 142 is journalled in ball bearings 145 and 146 and carries gear 143 at its upper end and pinion 141 at its lower end. Pinion 140 is secured on a spindle 148 which is journalled at one end in ball bearing 150 and at its other end in ball bearing 151.

A manually operated control lever 160 is journalled in body projection 161. A lever 160a is secured to the end of the control lever by a pin 162 and its lower bifurcated end straddles the flattened portion of stem 164 and is adapted to engage the shoulder 163 on stem 164. Stem 164 is slidably mounted through threaded plug 165, the inner end of which plug compresses a coil spring 166 against the inner annularly flanged portion 167 of stem 164 and the inner end portion 168 of the stem is adapted to fit into recess 169 in the side wall of the hammer when stem 164 is pushed inwardly against the pressure of spring 166, to halt sliding movement of the plunger, it being shown in such position in Fig. 2. In that position, the cams 64 and 65 will clear key 67 so that further rotation of the cams will not have any lifting effect on the plunger until the stem 164 is again moved outwardly from engagement with the recess by means of its spring 166.

In operation, the power to raise the hammer plunger, to operate the pump and to rotate the percussion tool, is transmitted by means of flexible shaft 80 which is operatively connected through pinion 74 and gear 75 to shaft 55. Upon rotation in a counter-clockwise direction, the cams 64 and 65 gradually engage keys 67 to raise the hammer plunger from the position of Fig. 5 to the position of Fig. 2, at which point the cams are suddenly disengaged from the keys to allow the fluid pressure within chamber 15 to force the plunger downward causing the plunger to strike

the anvil 36, which in turn acts against the upper end of the tool T. While shaft 55 is rotated to so rotate the cams, it is also, by virtue of crank 91 and connecting rod 90, operating the pump to maintain the fluid in chamber 15 under suitable compression, and, through gear 143, shaft 142, pinions 141, 140 and gear 122, continually rotating the tool T. In case the pressure within chamber 15 becomes excessive, it is automatically relieved by the pop-off valve 111, which may be adjusted by screwing plug 112 in or out to vary the compression on the valve spring. The device is extremely easy to assemble and cover plates 6, 8, 10, 12 and plug 61 make all the parts easily accessible.

My invention may be embodied in other specific forms without departing from the spirit or essential characteristics thereof. The present embodiment is therefore to be considered in all respects as illustrative and not restrictive, the scope of the invention being defined by the appended claims rather than by the foregoing description, and all changes which come within the meaning and range of equivalency are therefore intended to be embraced therein.

I claim:

1. A percussion device including a body having a cylinder bore therein and a fluid pressure chamber communicating with the bore, a piston slidably mounted in the bore, a drive shaft in the body, cam means on the shaft, said cam means cooperating with the piston to raise the same in the cylinder and disengage therefrom at a predetermined point in its travel to permit the fluid pressure within the chamber to force the piston downwardly, an anvil member engageable by the lower end of the piston, a rotatable member journalled in the body for slidably supporting a percussion tool, means operably connecting said rotatable member with said drive shaft whereby rotation of the drive shaft imparts rotation to the said rotatable member, a pump cylinder bore in the body, a pump plunger slidably mounted in the said latter bore, reciprocating means connected at one end to the drive shaft and at its other end to the pump plunger, a valve in the pump cylinder bore between the pump plunger and the fluid pressure chamber, said valve being operable by the up-stroke of the pump plunger to permit fluid to pass from the pump cylinder bore into the chamber, spring means automatically closing said valve as the pump plunger begins its downward stroke, and a fluid inlet port communicating with the pump cylinder bore at a point above the upper end of the pump plunger when said plunger is in its lowermost position in the cylinder bore.

2. A percussion device including a body having a cylinder bore therein and a fluid pressure chamber communicating with the bore, a piston slidably mounted in the bore, a drive shaft in the body, cam means on the shaft, said cam means cooperating with the piston to raise the same in the cylinder and disengage therefrom at a predetermined point in its travel to permit the fluid pressure within the chamber to force the piston downwardly, an anvil member engageable by the lower end of the piston, a rotatable member journalled in the body for slidably supporting a percussion tool, means operably connecting said rotatable member with said drive shaft whereby rotation of the drive shaft imparts rotation to the said rotatable member, a pump cylinder bore in the body, a pump plunger slidably mounted in the said latter bore, reciprocating means connected at one end to the drive shaft and at its

other end to the pump plunger, a valve in the pump cylinder bore between the pump plunger and the fluid pressure chamber, said valve being operable by the up-stroke of the pump plunger to permit fluid to pass from the pump cylinder bore into the chamber, spring means automatically closing said valve as the pump plunger begins its downward stroke, a fluid inlet port communicating with the pump cylinder bore at a point above the upper end of the pump plunger when said plunger is in its lowermost position in the cylinder bore, and a pressure relief valve in the body communicating from the chamber to atmosphere, said pressure relief valve being operable by fluid pressure within the chamber.

3. A percussion device comprising a body having a longitudinal cylinder bore therein, said bore having wall portions providing a fluid pressure chamber at the top end thereof, with which chamber the top end of the cylinder bore communicates, a hammer plunger mounted to reciprocate in said bore and forming a fluid tight closure for said bore at its point of communication with the chamber, a drive shaft journaled in and disposed transversely of the body, cam means on the drive shaft, said cam means cooperating with the hammer plunger to raise the same in the bore against the fluid pressure within the chamber, a pump in the body for maintaining fluid under pressure within the chamber, said pump being independent of the hammer plunger, and means operatively connecting said pump to the drive shaft whereby the pump is operated upon rotation of the drive shaft.

4. A percussion device comprising a body having a cylinder bore and walls defining a fluid pressure chamber in communication with said bore, a hammer plunger mounted to reciprocate in the bore, a continuously rotatable drive shaft journaled in the body, cam means on the drive shaft and cooperating with the hammer plunger to engage and raise the same, said hammer plunger being given its downward movement in the bore by virtue of the fluid pressure in said chamber, a pump communicating with the chamber to continuously charge the same with fluid under pressure, means operatively connecting the pump to the drive shaft whereby to operate the pump continuously, manually slideable control means mounted in the body for engagement with the hammer plunger when the hammer is in its raised position whereby to hold the hammer plunger

against movement in the bore without interfering with operation of the drive shaft and pump, said last mentioned means comprising a pin slidably mounted in the body for engagement with the hammer plunger, spring means normally holding the pin out of engagement with the hammer plunger, and manually operated lever means for moving the pin into engagement with the hammer plunger against action of the spring.

5. A percussion device including a body having a cylinder bore therein and a fluid pressure chamber communicating with the bore, a piston slidably mounted in the bore, a drive shaft in the body, cam means on the shaft, said cam means 10 cooperating with the piston to raise the same in the cylinder and disengage therefrom at a predetermined point in its travel to permit the fluid pressure within the chamber to force the piston downwardly, a pump cylinder bore in the body, a pump plunger slidably mounted in the said latter bore, reciprocating means connected at one end to the drive shaft and at its other end to the pump plunger, a valve in the pump cylinder bore between the pump plunger and the fluid pressure chamber, said valve being operable by the up-stroke of the pump plunger to permit fluid to pass from the pump cylinder bore into the chamber, spring means automatically closing said valve as the pump plunger begins its downward stroke, and a fluid inlet port communicating with the pump cylinder bore at a point above the upper end of the pump plunger, when the plunger is in its lowermost position in the cylinder bore.

6. A percussion device comprising a body, a cylinder bore therein, a plunger reciprocally mounted in the bore, walls forming a fluid pressure chamber in the body, the upper end of said bore opening into and having unrestricted communication with the chamber whereby to continuously expose the upper end of the plunger to the fluid pressure in the chamber to urge it downwardly in the bore, mechanical means for moving the plunger upwardly in the bore against said fluid pressure, means for continuously creating operating fluid pressure in the chamber, and a pressure-actuated release valve for releasing from the chamber any pressure in excess of a predetermined maximum operating pressure, said chamber being substantially closed against release of pressure therein so long as the pressure in the chamber does not exceed said maximum.

WILLIAM M. DRENNON.
